US0D1052973S

(12) **United States Design Patent** (10) **Patent No.:** **US D1,052,973 S**
(45) **Date of Patent:** **** Dec. 3, 2024**

(54) **MAGNETIC KNIFE HOLDER**

(71) Applicant: **Lijie Li**, Guangdong (CN)

(72) Inventor: **Lijie Li**, Guangdong (CN)

(**) Term: **15 Years**

(21) Appl. No.: **35/519,570**

(22) Filed: **Nov. 21, 2023**

(80) **Hague Agreement Data**

Int. Filing Date: **Nov. 21, 2023**

Int. Reg. No.: **DM/234046**

Int. Reg. Date: **Nov. 21, 2023**

Int. Reg. Pub. Date: **Dec. 29, 2023**

(30) **Foreign Application Priority Data**

May 24, 2023 (CN) 202330308825.X

(57) **CLAIM**

The ornamental design for a magnetic knife holder as shown and described.

DESCRIPTION

1. Magnetic knife holder

1.1 : Perspective

1.2 : Perspective

1.3 : Front

1.4 : Back

1.5 : Left

1.6 : Right

1.7 : Top

1.8 : Bottom

The design product is used for holding knives or other kitchen tools; the broken lines in the figures depict portions of the magnetic knife holder that form no part of the claimed design; the dot-dash broken lines in the figures show boundaries that form no part of the claimed design.

1 Claim, 8 Drawing Sheets
